UNITED STATES PATENT OFFICE.

VICTOR T. JOHNSON, OF MINNEAPOLIS, MINNESOTA.

MACHINE FOR FEEDING BOARDS.

SPECIFICATION forming part of Letters Patent No. 773,939, dated November 1, 1904.

Application filed December 11, 1903. Serial No. 184,750. (No model.)

To all whom it may concern:

Be it known that I, VICTOR T. JOHNSON, a citizen of the United States, residing at Minneapolis, in the county of Hennepin and State 5 of Minnesota, have invented certain new and useful Improvements in Machines for Feeding Boards; and I do hereby declare the following to be a full, clear, and exact description of the invention, such as will enable others skilled 10 in the art to which it appertains to make and use the same.

My invention has for its object to provide an improved board or lumber feeding device adapted for use in connection with planers, 15 edgers, horizontal band-saws, resawing-machines, and various other kinds of machines which are to act in one way or the other upon the boards or strips of lumber delivered thereto.

More specifically stated, my invention has 20 for its object to provide a board or lumber feeding device which will automatically feed boards one after the other and with the one board crowding the other, so that no gap is left 25 between them, and in which the initial movement of the one board is controlled or started by the passage of the next preceding or lower board. Such a feed device is especially 30 adapted for feeding box-lumber, wherein composite boards are made up of a plurality of narrow strips placed edge to edge.

To the above ends the invention consists 35 of the novel devices and combinations of devices hereinafter described, and defined in the claims.

The invention is illustrated in the accompanying drawings, wherein like characters indicate like parts throughout the several views.

Figure 1 is a plan view of the improved 40 feeding device or machine. Fig. 2 is a right side elevation of the same. Fig. 3 is a vertical longitudinal section on the line $x^3 x^3$ of Fig. 1. Fig. 4 is a transverse vertical section on the line $x^4 x^4$ of Fig. 2, some parts being broken away; and Fig. 5 is a transverse vertical section on the line $x^5 x^5$ of Fig. 2, some parts being broken away.

The numeral 1 indicates the heavy frame- 45 work, shown as made up of timbers and sup-

porting at its top a horizontally-extended bed-plate 2, which latter, as shown, is divided at 3 for a purpose which will presently appear. At the rear end of the frame 1—to wit, at the right-hand end as viewed in Figs. 55 1, 2, and 3—and at each side of the bed-plate 2 the said frame 1 rigidly supports inverted approximately U-shaped pedestals 4. Cross-heads 5 are mounted for vertical adjustments on the prongs or upright portions of the 60 pedestal-casting 4, and, as shown, these cross-heads are adjusted by screw-rods 6, having screw-threaded engagements therewith and swiveled at their upper ends in tie-bars 7, secured to the upper ends of the pedestals 4. 65 To impart common rotary movements to the two screw-rods 6, one thereof is provided with a hand-crank 8, and both thereof are provided with sprockets 9, over which sprockets a chain 10 is run.

A pair of lower feed-rollers 11 are suitably journaled in the bases of the pedestals 4, with their upper surfaces located slightly above the plane of the supporting-surface of the feed-table 2. An upper feed-roller 12 is suitably journaled in the vertically-adjustable cross-heads 5. The shafts of the three feed-rollers 11 and 12 project at one end and are provided, respectively, with sprocket-wheels 11^a and 12^a. The vertically-adjustable cross-heads 5 further carry a plurality of independently-movable spring-pressed rollers or presser-wheels 13, which wheels, as shown, are carried at the lower end of bell-crank levers 14, pivoted on a transverse shaft 15, secured at its ends to the said cross-heads. Springs 16, compressed between the upper ends of the levers 14, and a transverse reaction-bar 17, carried by vertical projections 5^a of said cross-heads, independently press the 90 presser wheels or rollers 13 into action, as will be hereinafter more fully set forth. The said cross-heads 5 also carry a transversely-extended stop-plate 18, the ends of which are rigidly secured to the forward portions of 95 said cross-heads. The lower edge of the stop-plate 18 terminates slightly above a horizontal plane which intersects tangentially the lower portions of the feed-rollers 12 and of the presser-wheels 13. Furthermore, the said 100

stop-plate is preferably inclined slightly from a vertical position, as best shown in Fig. 3.

Mounted in suitable bearings on the frame 1, below the lower feed-rollers 11, is a transversely-extended counter-shaft 19, which at one end is provided with a driving-pulley 20 and at its other end is provided with a sprocket 21, that alines with the heretofore-noted sprockets 11^a and 12^a. In line with the 10 sprockets just noted, but at the forward end of the machine, is an idle sprocket 22, shown as mounted on the stud of a bracket 23, secured to the frame 1. A long endless sprocket-chain 24 runs over the sprockets 12^a 21 22 15 and one of the sprockets 11^a and under the other sprockets 11^a, as clearly shown in Fig. 2, by reference to which it will be noted that the main portion of the upper part of the chain 24 extends horizontally along the upper 20 portion of the frame 1.

An adjustable box-like head 25 is mounted to slide from front to rear on the bed-plate 2, the same, as shown, having undeturned flanges 26 at its sides, which overlap with the 25 edges of the said bed-plate. At its intermediate portion the adjustable head 25 is provided with a depending nut-block 26^a, that works through the slot 3, formed between the sections of the bed-plate 2. A long adjusting-screw 27 works with screw-threaded engagement through the nut-block 26^a and at its ends is loosely journaled in transverse portions of the frame 1. At its forward ends the said screw-rod 27 is shown as provided 30 with a squared shank 28, to which a wrench or crank may be applied to turn the said screw-rod. Collars 29 on the said screw-rod engage on opposite sides of the transverse bar 1^a of the frame 1 to hold the said screw-rod 35 against endwise movement, so that when it is rotated the head 25 will be moved in the one direction or the other, according to the direction of rotation of said screw-rod 27. The rear wall of the head 25 is inclined to afford a 40 cam-acting feed-plate 30, the important function of which will more clearly appear later on.

A transversely-extended rock-shaft 31 extends through and is mounted in suitable bearings 25^a, carried by the adjustable head 25. 50 Just outward of the ends of the said head 25 the rock-shaft 31 is provided with arms 32, that are connected by short links 33 to the trunnions 34 of a wedge-shaped impelling-bar 35. The said wedge-shaped impelling-bar 35 55 slides over the inclined surface of the cam-plate 30, with its sharp edge turned upward. At one end the rock-shaft 31 is provided with an arm 36, upon which works an adjustable weight 37. At its other end said rock-shaft 60 is provided with an arm 38, shown as bifurcated, which carries a sprocket 39. This sprocket 39 normally rests loosely on the upper portion of the chain 24, and to connect it to the arm 38, which carries it, it is provided 65 with an eccentrically-located bolt 40, that

works adjustably in slots 41 of said arm. The said bolt 40 is of course provided with a suitable nut for setting it in any desired adjustment within the slots 41, formed in the prongs of the said lever 38.

In Figs. 2 and 3 the boards which are to be fed are indicated by the character *z*, one thereof being shown by full lines and another being shown by dotted lines.

The operation of the machine or feeding device as an entirety is substantially as follows: The boards *z*, whether they are made up of single sections or of a plurality of strips, are placed with their forward ends against the stop-plate 18 and with their rear ends resting on the inclined cam-plate 30. The head 25 should of course be adjusted for the particular length of board which is to be fed, so that the bottommost board can lie flat on the bed-plate 2 only when its rear end is pressed between the forward member of the lower presser-rollers 11 and the overlying yieldingly-mounted presser-wheels 13. Hence with this adjustment the second board from the bottom, the rear end of which will bear 85 against the stop-plate 18, will stand at a slight incline, with its forwardly-projecting end resting on the inclined cam-plate 30. Otherwise stated, the inclined cam-plate or surface 30 must be so set that its lower extremity stands 90 away from the board-engaging surfaces of the feed-rollers a distance less than the length of the boards which are to be fed to the rollers, while the upper extremity of said cam-plate should stand from the said rollers a greater 95 distance than the length of said boards, so that the outer ends of said boards may be rested thereon while they are held away from the rollers. With this arrangement whenever the lower board is fed rearward between the lower 100 rollers 11 and the upper roller 12 and presser-wheels 13 entirely beyond the rear end of the second board from the top—to wit, the one indicated by dotted lines in Figs. 2 and 3—the rear end of the said second board will immediately drop onto the bed-plate 2, and the cam-plate 30, acting on its forward end, will cam the said board thus dropped rearward, so that its rear end will be caught and pressed between the first roller 11 and the overlying 105 presser-wheels 13 and in this way will be taken up and fed rearward by the feed-rollers, with its rear end abutting against the forward end of the board which has just succeeded it in its rearward movement. To further insure and to make more positive the above-described continuous feeding action of the boards, the wedge-shaped impelling-bar 35 and its actuating means are provided, and this device operates as follows: While the one 110 board is being fed rearward between the feed-rollers the sprocket-chain 24, acting on the eccentric sprocket 39, rotates the same, thereby raising the lever 41, arms 39, and the impelling-bar 35. Under this upward move- 115

ment the said impelling-bar 35 crowds itself along the cam-plate 30 and under the forwardly-projecting end of the second board from the bottom and when it has reached its 5 uppermost position stands with its thick edge pressed against the raised forwardly-projecting end of said second board from the bottom, with the force of the weight 37 on the rock-shaft arm 36, tending to force it downward 10 and in turn tending to cause it to force the engaged board rearward. The chain acting on the sprocket 39 at this time will slip along under the loosely-depend ing sprocket, but, as is obvious, will be powerless to cause the said 15 sprocket to lower. When, however, the lower board passes beyond the rear end of the said second board and the rear end of the said second board is permitted to drop, the weight 37, acting on the impelling-bar 35, coöperates 20 with the cam-plate 30 to force the forwardly-projecting end of the engaged board downward and rearward, so that the said board will immediately follow the preceding board between the feed-rollers. As is evident, when 25 the impelling-bar 35 is thus thrown downward to its extreme lower position the sprocket 39 is also dropped to its lowermost position, so that the chain 24, acting thereon, will again raise the said impelling-bar 35. The said impelling-bar under the action above described 30 has what might be termed a "ratchet" action on the boards, inasmuch as it slips thereunder in one direction and engages and positively feeds the same in the opposite direction. 35

The plurality of independently-spring-mounted presser-wheels 13 is especially important when composite boards made up of a plurality of strips are to be fed as entireties 40 between the feed-rollers. In any case, however, they insure frictional engagements with the boards at a great many different points.

By adjusting the bolt 40 in the slots of the arm 38 the length of stroke which will be 45 given to the impelling-bar 35 may be varied to adapt it for action on boards of different thickness. Again, by vertical adjustments of the cross-heads 5 the upper feed-roller 12 and the presser-wheels 13 may be adjusted for 50 proper action on boards of different thickness. There will be sufficient slack in the chain 24 to permit such vertical adjustments of the cross-heads 5 as are usually necessary; but if greater movements are required than the chain 55 will permit under the arrangement shown a link of the chain may be taken out or one may be added, or, if desired, a chain-tightener may be provided.

It has already been plainly indicated that 60 the so-called "impelling device" or means for producing the initial feed movement of the boards is timed for action by the movement of the particular board which is being fed rearward by the feed-rollers. Otherwise 65 stated, the said impelling device or initial feed-

producing device is set for action and will come into action as soon as it is permitted to do so by the passage of the lower board out from under the board which is immediately above it and which is subject to the said impelling device. 70

From what has been said it will be understood that the machine described is capable of many modifications within the scope of my invention as herein set forth and claimed. 75

What I claim, and desire to secure by Letters Patent of the United States, is as follows:

1. The combination with feed-rollers, of means for feeding boards thereto, including 80 an impelling device for action on the lower board, to impart initial feed movements thereto; and mechanism for setting said impelling device under strain, to produce an initial feed movement of the lower board, as soon as the said board is released by the passage of the preceding board from underneath the same, substantially as described. 85

2. The combination with feed-rollers and an adjacent stop holding back the upper boards, 90 of an impelling device for action on the lower board, to impart initial feed movements thereto, and means for setting said impelling device under strain to produce the initial feed movement of said lower board, as soon as the said board is released by the passage from under the same of a preceding board, substantially as described. 95

3. The combination with feed-rollers and an adjacent stop holding back therefrom all but 100 the lower board, of an inclined cam-surface engaging the other ends of the boards and tending to force the same rearward to said feed-rollers, and an impelling device adapted to be set while a lower board is being fed, for action 105 on the next board above, to impart thereto an initial feed movement, as soon as the preceding board has passed from under the same, substantially as described. 110

4. The combination with a bed-plate and feed-rollers, of a stop in the vicinity of said feed-rollers engaging the ends of the boards and permitting only the lower board to pass to 115 said rollers, an inclined cam-surface engaging and supporting the boards at their other ends and tending to crowd the same toward said rollers, a vibrating impelling-bar working over said cam-surface and acting on the ends of the said boards, and means for setting said impelling-bar for action on an upper board, 120 while the preceding lower board is being fed from under the same, the said impelling device becoming active as soon as the said preceding board has been fed beyond the bar-engaged board, substantially as described. 125

5. The combination with feed-rollers and an adjacent stop holding back all but the lower board, of an inclined cam-surface acting on the boards at their other ends and tending to force the same toward said feed-rollers, a 130

wedge-shaped impelling-bar working over said inclined surface, a rock-shaft connected to the ends of said impelling-bar, for reciprocating the same, a weighted arm acting on the said rock-shaft and tending to lower said impelling-bar to produce an initial feed movement of the engaged board, and means for rocking said shaft to set said impelling-bar for action on an upper board, while the preceding lower board is being fed, substantially as described.

6. The combination with a bed-plate, feed-rollers and a sprocket-chain driven from said feed-rollers, of a stop in the vicinity of said rollers holding back all but the lower board, an inclined cam-surface engaging the other ends of the boards and tending to crowd the same toward said feed-rollers, a wedge-shaped impelling-bar working over said cam-surface, a rock-shaft having connections with the ends of said impelling-bar, a weight acting on said rock-shaft, an arm on said rock-shaft, and an eccentric sprocket mounted on said arm and engaging with said sprocket-chain, to raise said impelling-bar and set the same for action to impart initial feed movements to the board, under the force of said weight, substantially as described.

7. The combination with feed-rollers and a stop engaging the ends of the boards in the vicinity thereof and permitting only the lower

board to be fed to said rollers, of an impelling-bar operating on the other ends of said boards, to impart initial feed movements thereto, and means for setting said impelling-bar under strain to produce the initial feed movement of said board, as soon as the said board is released by the passage from under the same of the preceding board, substantially as described.

8. The combination with a bed-plate or support, and feed-rollers, of means for holding the boards and delivering the same to said feed-rollers one at a time, including an inclined cam-surface, set with its lower extremity a less distance, and its upper surface a greater distance, from the board-engaging surfaces of said feed-rollers than the length of the boards being fed, whereby said inclined cam-surface engages and supports said boards at their outer ends and tends to crowd the same forward to said feed-rollers, as soon as a lower board is released by the passage of a preceding board from underneath the same, substantially as described.

In testimony whereof I affix my signature in presence of two witnesses.

VICTOR T. JOHNSON.
